CLAIM

The ornamental design for a backhoe loader, as shown and described.

DESCRIPTION

FIG. 1.1 is a front view of a backhoe loader, in accordance with the present design;

FIG. 1.2 is a back view of the backhoe loader, shown in FIG. 1.1;

FIG. 1.3 is a left side view of the backhoe loader, shown in FIG. 1.1;

FIG. 1.4 is a right side view of the backhoe loader, shown in FIG. 1.1;

FIG. 1.5 is a top view of the backhoe loader, shown in FIG. 1.1;

(Continued)

FIG. 1.6 is a perspective top view of the backhoe loader, shown in FIG. 1.1.
